UNITED STATES PATENT OFFICE.

JAMES PEARSON, OF CLEVELAND, OHIO, ASSIGNOR TO THE WARNER AND SWASEY CO., OF CLEVELAND, OHIO, A CORPORATION OF OHIO.

AUTOMATIC CHUCK.

SPECIFICATION forming part of Letters Patent No. 790,656, dated May 23, 1905.

Application filed October 12, 1903. Serial No. 176,621.

To all whom it may concern:

Be it known that I, JAMES PEARSON, a citizen of the United States, residing at Cleveland, in the county of Cuyahoga and State of Ohio, have invented a certain new and useful Improvement in Automatic Chucks, of which the following is a full, clear, and exact description, reference being had to the accompanying drawings.

Automatic chucks such as have been in common use for many years have certain characteristics which are in the nature of defects. Perhaps the most objectionable characteristic is the liability of the spring-jaws to break. Another undesirable characteristic is that it is necessary to almost dismantle and rebuild the front end of the live-spindle in order to adapt the same for stock rods of larger or smaller diameter. Another defect is that if the stock rods being worked are not exactly uniform in diameter the length of rod which projects beyond the chuck-jaws after they have firmly grasped it is not always the same.

The object of this invention is to provide a chuck which is durable, in which the jaws are easily removable and replaceable, and which have no endwise motion as they grip the stock rod.

The invention, which is illustrated in the drawings and hereinafter described, may be here summarized as consisting in the construction and combination of parts definitely set forth in the claims.

In the drawings, Figure 1 is a longitudinal central section of the front end of a live-spindle containing my invention. Fig. 2 is a transverse section in the plane indicated by line 2 2 of Fig. 1, and Fig. 3 is a detached view of the sleeve E.

Referring to the parts by letters, A represents the tubular live-spindle of a screw-machine, turret-lathe, or the like. Within this spindle is the longitudinal movable tube C, common in devices of this character, the function of which is to cause the operation of the compression member B by its forward movement in the spindle. The compression member B is a tube which is fitted into the spin-

dle and is capable of being moved endwise 50 therein by the endwise movement of said tube C. The front end of the tube B is conically flaring—that is to say, it is internally tapered—and is largest at its front end. It may be prevented from rotating within the spindle by a screw F, which enters a longitudinal slot in the tube B, and thereby does not interfere with the longitudinal movement of said tube. Within the flaring front end of the tube B are four, more or less, independent chuck-jaws D, which jaws externally are tapered to substantially fit the tapered interior of the tube B. These jaws are of segmental form of such width that they do not entirely complete the circle when in place, as 65 shown. In their proximate edges are longitudinal slots d, which extend from their rear ends forward. A sleeve E is fitted within the tube B, and it has forwardly-projecting spring-arms e, which enter the groove d of two adjacent chuck-jaws. These arms prevent the jaws from falling inward and, in fact, by their spring action hold them in contact with the flaring inner surface of the tube B. The front end of this sleeve E abuts against the rear 75 end of the jaws. A ring G screws into the front end of the spindle and abuts the annular shoulders d' on the chuck-jaws, and thus prevents them from coming out of the spindle. A coiled spring K is placed within the 80 tube B, and it exerts its force against the rear end of the sleeve E and an internal flange b on the tube B. The result is that the sleeve E is forced forward, and it in turn forces the chuck-jaws forward into contact with the 85 ring G, and this spring also forces the tube B rearward, so as to allow the chuck-jaws to expand to their fullest capacity.

The stock rod is fed forward through the tubes C and B and the sleeve E and chuck-jaws. When it projects far enough, the tube C is moved forward in the spindle by any suitable instrumentality—as, for example, the fingers commonly employed for this purpose. The tube B is thereby moved forward, with 95 the result of causing the chuck-jaws to contract upon the stock rod and to hold it firmly. When it is desired to release the stock rod,

the tube C is allowed to move rearward, whereupon the spring K moves the tube B rearward, thereby allowing the chuck-jaws to open. When it is desired to adapt the spindle for stock rods of different diameter, it is only necessary to unscrew the ring G and to substitute chuck-jaws of less or greater thickness, so that the internal diameter of the space inside said jaws shall be greater or less, as desired.

Having described my invention, I claim—

1. The combination, with the tubular live-spindle of a screw-machine or the like, of a plurality of independent segmental chuck-jaws having tapered exterior surfaces and having longitudinal grooves in their proximate edges extending from their rear ends forward, means preventing the forward movement of said chucking-jaws, a tube within said spindle which abuts the rear end of said jaws and has forwardly-projecting arms which enter said slots, a longitudinally-movable compression-tube which embraces and extends rearward beyond the tube first named and has a flaring front end which embraces said jaws, and an inwardly-turned flange on its rear end, a spring compressed between said flange and the rear end of the arm carrying the tube.
2. The combination, with the tubular live-spindle of a screw-machine or the like, of a plurality of independent segmental chuck-jaws having outwardly-extended flanges near their front ends, and, behind them, tapered convex exterior surfaces, and longitudinal

slots in their proximate edges, a ring which screws into the end of the spindle against the shoulders on said jaws, a longitudinally-movable compression member within said spindle having a flaring front end which embraces said jaws, a tube within said compression member having forwardly-extended spring-arms which enter the slots in the edges of said jaws, means, preventing the rotation of said compression member, and a spring acting to move the compression member rearward and said tube forward.

3. The combination, with the tubular live-spindle of a screw-machine or the like, a plurality of segmental chuck-jaws having recesses which open from their rear ends, a tube within the spindle having forwardly-projecting spring-arms which enter said recess and prevent the jaws from falling inward, and a compression member for forcing said jaws inward.

4. The combination, with the tubular live-spindle of a screw-machine or the like, of a plurality of segmental chuck-jaws having longitudinally-grooved proximate edges, a tube within the spindle having forwardly-projecting arms which span the intervals between said jaws and project into said grooves, and mechanism for forcing said jaws inward.

In testimony whereof I hereunto affix my signature in the presence of two witnesses.

JAMES PEARSON.
